UNITED STATES PATENT OFFICE.

EBENEZER HILL, OF NORWALK, CONNECTICUT.

STEAM-ENGINE VALVE-GEAR.

No. 800,301.

Specification of Letters Patent.

Patented Sept. 26, 1905.

Application filed February 17, 1905. Serial No. 246,058.

To all whom it may concern:

Be it known that I, EBENEZER HILL, a citizen of the United States, residing at Norwalk, in the county of Fairfield and State of Connecticut, have invented a new and useful Steam-Engine Valve-Gear, of which the following is a specification.

This invention relates to a valve-gear of the Corliss-engine type.

10 The object of this invention is to provide an efficient valve-gear for steam-engines of the Corliss type which under the control of the governor will cut off steam at any point from zero to full stroke. This object is attained by arranging the mechanism which changes the position of the trips so as to operate with the mechanism that opens the valves, but at the same time under the control of a governor operate independently of the valve-opening mechanism in such manner that the time of action of the trip mechanism with relation to the time of action of the valve-opening mechanism will be retarded or advanced from about zero to one hundred and 20 eighty degrees according to the demand of the engine for more or less steam.

25 Figure 1 of the accompanying drawings represents a side elevation of an engine provided with a valve-gear which embodies this invention. Fig. 2 shows, on larger scale, a side elevation of the mechanism adjacent to one of the steam-inlet valves. Fig. 3 shows a plan of the valve mechanism. Fig. 4 shows the valve-stem arm and catch. Fig. 5 shows the valve-opening latch. Fig. 6 shows the latch-trip and trip-arm. Fig. 7 shows the mechanism adjacent to the eccentric and the governor. Fig. 8 shows, on larger scale, the eccentric mechanism. Fig. 9 shows a plan of the eccentric mechanism. Fig. 10 shows the latch-lever and latch. Fig. 11 shows side and plan views of the valve-stem arm and catch. Fig. 12 shows the trip and trip-arm. Fig. 13 shows the wrist-plate. Fig. 14 shows a side view of the wrist-plate levers. Fig. 15 shows a section of the wrist-plate and wrist-plate levers.

On the outer end of the stem 1 of each steam-inlet valve is a loose lever 2. One end of each of these levers is connected by a link 3 with a wrist-plate 4. Pivotally hung on the other end of each of these levers is a hooked latch 5, which has a releasing-finger 6, Figs. 1, 2, 5, 10. Keyed to each valve-stem is an arm 7, with a catch 8, that is adapted 55 to be engaged by the latch which is forced

toward the catch by a spring 9. A rod 10 connects each of the valve-stem catch-arms with a piston in a vacuum dash-pot, Figs. 1, 2, 4, 11. Loosely mounted on each valve-stem is a ring 12, which in the plane of movement of the latch-releasing finger has a trip 13 and an arm 14. Each of these arms is by a link 15 connected with the upper end of a lever 16, which is attached to the inner end of a shaft 17, that is carried by the wrist-plate. On the outer end of this floating shaft is a lever 18, Figs. 1, 2, 6, 12. The oscillation of the wrist-plate through the links oscillates the latch-levers and causes the latches to engage the catches and lift the arms and open the valves. The oscillation of the floating levers through the links oscillates the trip-arms and trips. When a trip is oscillated into the path of and engages the releasing-finger of a latch, that latch is disengaged from the catch, so that the vacuum in the dash-pot produced by lifting the arm or other suitable mechanism which is commonly employed for this purpose will cause the rod to pull down the catch-arm and close the valve. When the trip is oscillated out of the way, the latch can again hook onto the catch and when lifted open the valve.

In the particular form of engine illustrated the lower end of the wrist-plate is by a rod 19 connected with a rocker-arm 20 on a shaft 21, which has a rocker-arm 22, that is connected by the eccentric-rod 23 with the eccentric 24. This eccentric is a stud on the return-crank 25, that is attached to the main crank-pin 26 in such manner that the eccentric is approximately ninety degrees in advance of the crank. The rotation of this eccentric through the eccentric-rod and connecting-rod oscillates the wrist-plate that is connected with the latch-levers and which supports the levers that are connected with the trip-arms, Figs. 1, 7. The lower end of the floating lever 18 is by a rod 27 connected with a rocker-arm 28 on a shaft 29, that has a rocker-arm 30, which is connected by an eccentric-rod 31 with an eccentric 32. This eccentric is loosely mounted on a pin 33, which projects concentric with the main eccentric-stud on the return-crank, Figs. 1, 7. The bell-crank connections between the wrist-plate and main or valve-opening eccentric and between the floating lever and auxiliary or trip eccentric are mere details of transmission and are not material to the invention.

By mounting the trip-eccentric on the valve-eccentric the throw of the former will always be the same with respect to the throw of the latter, and the amount of movement of the floating levers with respect to the amount of movement of the wrist-plate will always be the same, although the movement of the floating levers through space will vary according to the position of the trip-eccentric with relation to the valve-eccentric. 5

Attached to the eccentric 32 is a gear 34, which meshes with an intermediate gear 35, that meshes with a gear 36, the center of which is coincident with the center of the shaft. The gear 36 is keyed to a shaft 37, supported 10 by the plate 38, on which shaft is an arm 39, that by a rod 40 is connected with the governor-lever 41, Figs. 1, 7. As long as the demand for steam is uniform the arm 38 and the gear 36 are held in one position. With 15 these in one position the eccentric 32 operates the same at each revolution with relation to the eccentric 24 and causes the trips to release the latches from the catches and allow the dash-pots to close the valves at the same 20 place during each stroke. If the demand for steam increases or diminishes and the governor changes, the gear 36 is rotated and through the intermediate gear 35 rotates the gear 34 and the eccentric 32 in a direction depending upon whether the governor-lever is raised or lowered, and this changes the relation of the eccentric 32 to the eccentric 34 and causes such a change in the time of movement of the trips that the latches are 25 released from the catches at a different place. As the throw of the eccentric 32 can be changed one hundred and eighty degrees or one-half a revolution with relation to the throw of the eccentric 24 by means of the 30 governor, the trips may engage and release the latches anywhere during one-half of a revolution of the crank-shaft or from zero to full stroke of the piston. In this construction the trips which release the catches have an 35 oscillating movement about the axis of the valves and pass into the paths of the latch-releasing fingers every stroke and at some time come in contact with them, so as to release the latches and allow the valves to close. 40

The time of release will depend upon the time of contact of the trips with the releasing-fingers, and this depends upon the relative positions of the valve-eccentric and the trip-eccentric which is controlled by the governor. 45

If the engine demands more steam, the governor draws back the trip-eccentric, so that the trips will not engage the latches as early during the stroke. If the engine does not need as much steam, the governor advances 50 the trip-eccentric and this causes the trips to

engage the latches sooner and causes the steam to be cut off earlier during the stroke. 55

The invention claimed is—

1. An engine valve-gear having an eccentric for opening the valves, a shifting eccentric carried by the valve-opening eccentric for tripping the valves and allowing them to close, and means for shifting the tripping-eccentric, substantially as specified. 70

2. An engine valve-gear having an eccentric for opening the valves, a shifting eccentric carried by the valve-opening eccentric for tripping the valves and allowing them to close, and a governor for shifting the tripping-eccentric, substantially as specified. 75

3. An engine valve - gear having a wrist-plate arranged to open the valves, an eccentric for oscillating the wrist-plate, floating levers carried by the wrist-plate and arranged to trip the valves and allow them to close, and a shifting eccentric carried by the valve-opening eccentric for oscillating the floating levers, 80 substantially as specified. 85

4. An engine valve - gear having a wrist-plate arranged to open the valves, an eccentric for oscillating the wrist-plate, floating levers carried by the wrist-plate and arranged to trip the valves and allow them to close, a shifting eccentric carried by the valve-opening eccentric for oscillating the floating levers, 90 and a governor for shifting the tripping-eccentric, substantially as specified. 95

5. An engine valve-gear having an eccentric for opening the valves, a shifting eccentric carried by the valve-opening eccentric for tripping the valves and allowing them to close, 100 intermeshing gears connected with the shifting eccentric, and a governor connected with the gears, substantially as specified.

6. An engine valve-gear having an eccentric for opening the valves, a shifting eccentric carried by the valve-opening eccentric for tripping the valves and allowing them to close, a gear connected with the tripping-eccentric, a governor, a gear connected with the governor, and a gear meshing with the governor-gear and the eccentric-gear, substantially as specified. 110

7. An engine valve-gear having latches arranged to open the valves, an eccentric connected with and adapted to cause the latches to open the valves, trips arranged to release the latches and allow the valves to close, an eccentric carried by the valve-opening eccentric and connected with the trips, and a governor connected with the trip-eccentric, substantially as specified. 115

8. An engine valve-gear having an eccentric for opening the valves, an eccentric hung on the center of the valve-opening eccentric and adapted to trip the valves and allow them to close, a gear attached to the shifting eccentric, an intermediate gear meshing with the eccentric-gear, a gear with its axis coincident with the axis of the shaft meshing with the 120 125 130

intermediate gear, and a governor arranged to oscillate the gear which is concentric with the shaft, substantially as specified.

9. An engine valve-gear having latches arranged to open the valves, an eccentric connected with and arranged to cause the latches to open the valves, trips arranged to release the latches and allow the valves to close, and an eccentric rotating with and also independently of the latch-operating eccentric and connected with and arranged to oscillate the trips, substantially as specified.

10. An engine valve-gear having latches ar-

ranged to open the valves, an eccentric connected with the latches and arranged to cause them to open the valves, trips arranged to release the latches and allow the valves to close, an eccentric rotating with and also independently of the latch-operating eccentric and connected with and arranged to oscillate the trips, and a governor connected with the trip-eccentric, substantially as specified.
